UNITED STATES PATENT OFFICE.

VICTOR J. JANSER AND HENRY MEYER, OF SPRINGFIELD, MASSACHUSETTS.

GUARD ATTACHMENT FOR CHANDELIER.

No. 807,173.

Specification of Letters Patent.

Patented Dec. 12, 1905.

Application filed February 24, 1905. Serial No. 247,108.

To all whom it may concern:

Be it known that we, VICTOR J. JANSER and HENRY MEYER, citizens of the United States of America, and residents of Springfield, in the county of Hampden and State of Massachusetts, have invented certain new and useful Improvements in Guard Attachments for Chandeliers, of which the following is a full, clear, and exact description.

10 This invention relates to improvements in guards and supporting appliances therefor to be combined with a depending pipe of a chandelier or gas-light and which serve to prevent the smoke and heat from the gas light or 15 lights from blackening or otherwise injuriously affecting the ceiling above the chandelier.

20 A particular object of this invention is to provide supporting appliances for the gas-light guards or canopies which permit the positioning of the guards in any proper radial adjustment to accord with the location of the burners, more or less, as the case may be, outwardly beyond the central line of the 25 depending gas-pipe.

Other objects of the invention are to the 30 end of securing simplicity of construction, practicability and convenience in setting up, durability, and the capability of compactly arranging the parts for stowage or transportation.

The invention consists in the constructions and combination of parts hereinafter described, and set forth in the claims.

35 In the accompanying drawings, Figure 1 is a side elevation of a chandelier having the present improved gas-light guards combined therewith. Fig. 2 is a plan view and partial section showing the primary support for the 40 guard-carrying rods as constructed for a three-light chandelier and showing one of the guard-carrying rods. Fig. 3 is a side view of one of the guard-carrying rods.

Similar characters of reference indicate corresponding parts in all of the views.

In the drawings, A represents a chandelier comprising the depending gas-pipe B and having at its lower end the radiating branch pipes C C, provided, as usual, with the gas- 50 burners D D and globes E E therefor.

G represents a primary support for the rods F F, which carry at their outer ends the guards or canopies J to have positions suitably above and directly over the gas-light.

As shown in the form of its most extensive 55 construction, the said support G is made in the form of a sleeve comprising the section a and a second section a', hinge-connected at b, one of said sections having a tongue-shaped extremity d to match into an endwise-opening recess f in the other section, said matching parts being vertically perforated to receive therethrough the locking-pin g. The sectionally-constructed sleeve has radial screw-threaded openings i therethrough, through 65 which are screw-engaged the threaded shanks or members j, which have formed as one therewith or attached thereto the straight tubular extensions k, open at their outer ends.

The straight portions of the rods F have engagements telescopically with the tubular extensions k, so that either inward or outward movements of such rods will bring the canopy-guards J to their proper positions directly over the burner.

As shown in Figs. 2 and 3, the ends of the rods F are split, as indicated at x, the portions at either side of the cleft being normally deflected or spread, as more particularly shown in Fig. 3, and thereby adapted on the contraction of the spread portions in their entrance into the tube k to develop a frictional reaction for the adjustable confinement in the tubular extensions of the guard-carrying rods, it being manifest that this frictional engagement 85 is such as to not only maintain the rods against undue endwise movements, but keeps them from rotational movements, whereby the guards J would be improperly tilted.

The threaded extremities of the studs j (of 90 which there are at least three, although four thereof might be provided for substantially similar effects) protrude beyond the inner wall of the sleeve in the engagement of the appliance with and about the depending gas-pipe 95 B and bind against such pipe at different sides thereof, serving as the supporting means for the sleeve and the parts carried thereby. The extensions of the always sufficiently long shanks of the studs entirely through and beyond the inner wall of the sleeve make it practicable, as clearly understood in Fig. 2, to make the appliances with the sleeves as large or larger than the largest gas-pipes and render them applicable as well on very small 100 as on medium or the largest gas-pipes in use, and thus the practical value of the present improved device largely depends on its applica- 105

bility as well on a quarter-inch drop-pipe as on one of an inch or approximately the size of the round opening within the sleeve.

As apparent, the guards J and their carrying-rods may be easily drawn out from the tubular extensions k, which latter may be disconnected from the sleeve, and the sleeve on being disconnected from the pipe may, with the parts j k and F J, be compactly disposed 15 in a box or package for stowage in a store or for transportation.

It is to be especially stated that by making the stud j serve the double purpose of a universally-applicable confinement means for the 25 sleeve relatively to the drop-pipe and also as parts comprised in the supporting means for the guards J, an attachment is produced in which the components are reduced to a minimum, with corresponding advantages both to 30 the manufacturer, to point of cheapness of construction, and to the user because of simplicity and lessened liability to derangement in use.

Having thus described our invention, what 25 we claim, and desire to secure by Letters Patent, is—

1. In an appliance of the character described, a sleeve or ring made in hinge-connected sections, provided with means for locking the 30 sleeve-sections in their closed relations, and formed with three or more holes radially therethrough, three or more studs having threaded shanks screw - engaged through said radial holes and protruding beyond the inner wall 35 of the sleeve to assume engagements with the depending chandelier gas-pipe to secure the appliance to said pipe, at different points there-around, and said studs being provided with tubular extensions, and rods, endwise adjust-

able in said tubular extensions and carrying 40 guards or canopies at their outer ends.

2. In an appliance of the character described, in combination, a sleeve or ring made in hinge-connected sections and provided with means for locking the sections closed, and constructed 45 with three or more screw-threaded holes therethrough, a corresponding number of studs having threaded shanks screw-engaged through said radial holes, and protruding beyond the inner wall of the sleeve for engagement with 50 variably-sized chandelier-pipes to secure the appliance to said pipes said studs having the outwardly-open axial sockets, tubular arms having their inner ends engaged in said sockets, and the rods frictionally engaged, and 55 endwise adjustable, in said tubes and having gas-light guards at their outer ends.

3. In an appliance of the character described, a supporting-ring comprising a plurality of movably-connected segments, and means to 60 secure said segments together, said segments being formed with a plurality of radially-disposed threaded openings extending entirely therethrough, a plurality of radiating studs, each of which is formed with a threaded end 65 engaging one of said openings and projecting within the segmental ring to impinge against a pipe to secure the appliance in position thereon, the outer end of each stud being formed with an axial socket, arms rigidly mounted in 70 the sockets and shields on the arms.

Signed by us at Springfield, Massachusetts, in presence of two subscribing witnesses.
